DRAWING MECHANISM FOR TEXTILE
SLIVERS OR ROVINGS

John Frederick Jackson, Pawtucket, R. I., assignor to H & B American Machine Company, a corporation of Maine

Application June 16, 1937, Serial No. 148,524

3 Claims. (Cl. 19—131)

This invention relates to drawing mechanisms for textile slivers or rovings; and has for one of its objects the provision of an improved construction of drafting apparatus utilizing belts or aprons in which each of the individual belts or aprons employed for supporting and carrying the strand of sliver or roving from one pair of drawing rolls to another, are of an endless construction.

Another object of the invention is to provide simple and improved support means for guiding the belts whereby they may be easily removed and replaced at will without interrupting the normal operation of the other sections of the machine or necessitating stoppage of the complete machine with the consequent loss of production and expense which has heretofore been the case during use of the prior art belt mechanisms employing belts or aprons the ends of which are cemented together after being put in place.

Another object of the invention is to provide a device which is readily attachable and detachable on the machine and applied between adjacent pairs of drawing rolls whereby the assembly of endless belts and their associated rotatable driving members may be bodily removed as a complete unit from the machine.

Another object of the invention is to provide a unit device containing endless feeding belts, driving members, and a guide support therefor that is so constructed to be completely devoid of any mechanism requiring attachment to or having embracing relation with a fixed driving roll on the machine to be upheld thereby.

Another object of the invention is to provide a device of the above type constructed with a plurality of sets of endless belts each set of which has cooperating runs between which the sliver or roving travels in which the arrangement is such that one of the rotatable members for driving one of the belts of each set has positive driving connection with a single elongated continuous drive shaft disposed beneath the particular driven rotatable member for the respective belt.

Another object of the invention is to provide a device so constructed that spaced sets of guide supports are provided about which run the forward bight of each of the endless belts travels in which the guide supports of each set are carried by separate cradle frames which guide the movements of each set of belts and are detachably supported solely by the removable rotatable cylinder members for driving the belts whereby

all the belts may be applied in an endless form.

Another object of the invention is to provide a sliver feeding mechanism of the above type which is removable bodily as a unit from its support on the machine whereby the endless belts serve solely to maintain the parts in assembly when the unit is taken out of the machine.

With these and other objects in view, the invention consists of certain novel features of construction, as will be more fully described, and particularly pointed out in the appended claims.

In the accompanying drawings:

Fig. 1 is a vertical sectional view looking at the end of the drafting rolls, and showing the roll stand in which there is applied thereto and positioned in operating position one form of unit drafting mechanism embodying my invention;

Fig. 2 is a front longitudinal sectional view taken on the line 2—2 of Fig. 1 showing my feeding device and with their rotatable members for driving the belts and the manner in which the latter are driven;

Fig. 3 is a front longitudinal sectional view taken on the line 3—3 of Fig. 1;

Fig. 4 is a longitudinal sectional view taken on the line 4—4 of Fig. 1;

Fig. 5 is a perspective view of a belt mechanism embodying my invention;

Fig. 6 is a perspective view of one of the side plate members of the cradle frame;

Fig. 7 is a perspective view of the guide support for the upper and lower belts;

Fig. 8 is a perspective view of the companion side plate of the set of the cradle frame shown in Fig. 5;

Fig. 9 is a modified form of side plate of a cradle frame which may be used in place of that shown in Fig. 6; and

Fig. 10 is a modified form of guide support for the upper and lower belts and adapted for use with the side plate shown in Fig. 9.

Heretofore, in the construction and operation of the common forms of apparatus of this class utilizing endless belts or aprons, such members have been usually guided and supported by a frame or cradle having side plates for confining the belts and rigidly joined together by suitable rods and guide bars to provide a unitary structure. This frame or cradle, furthermore, is commonly provided with a pair of detachable bars or rods at its forward portion over which the front loop of the belts is guided in close proximity to the drawing rolls. However, in the machines employing this prior arrangement the lower roll carrying the bottom belt has usually consisted of

- a single elongated fluted roll which ordinarily extends substantially the entire length of the machine and is made up of a series of sections joined together at their ends for driving connection.
- 5 The upper roll usually is short and formed with a pair of spaced belt engaging portions, this roll is loosely mounted at its ends in the usual cap bars and consequently is easily removable therefrom to permit insertion in the loop of the upper belt, 10 which thus may be initially made endless by cementing of the ends together. Owing to the great length and unitary construction of the lower roll around which the bottom belt runs, it is impractical to employ a previously fabricated 15 endless apron or belt in this location, thus making it necessary to cement the ends of the belt in place each time it is renewed, which process requires stopping the machine with the attendant loss of production; and in order to provide a construction 20 which is particularly suitable for such drafting apparatus and to improve and simplify such belt mounting construction, I have provided a unit device of a "floating" type of construction employing an exterior driving roll for 25 the belt cylinders and wherein a plurality of pairs of belts are arranged separated in spaced positions with each pair in cooperating relation and guided between a cradle device so arranged that the side plates thereof guide the belts against 30 lateral slipping and carry the guide supports for the forward loops of the belts, in which such cradle is constructed to receive and be supported entirely by the insertable driving rolls for the endless belts and not to rest on and be carried 35 by any single fixed continuous roll extending the entire length of the machine, as has heretofore been the previous arrangement with the result that endless belts could not be used on the lower roll, thus preventing the raising and removal of 40 the entire assembly as a unit; and the following is a more detailed description of the present embodiment of this invention, illustrating the preferred means by which these advantageous results may be accomplished:
- 45 With reference to the drawings, 10 designates one of a series of spaced roll stands which is well known construction in the art each having a standard 11 provided with a suitable base portion (not shown) whereby each of the stands may 50 be rigidly mounted on a suitable support of the frame of the machine. As shown in Fig. 1 each roll stand is provided with a top platform member 12 having its forward end extending upwardly to form the usual journal for the front bottom rolls 55 13. At the rear of each of the roll stands and on the platform 12 is adjustably secured a bearing block 15 on which is journaled the bottom back roll 16. The rolls 13 and 16 may be formed either with a smooth cylindrical outer surface or 60 of a fluted construction, as desired. This block 15 is formed at its bottom with a suitable longitudinally extending channel for interfitting seating engagement with a cooperating tongue portion on the upper face portion of the platform 12 65 of the roll stand, as is the usual construction in the art. The forward portion of this block 15 is of reduced thickness and at the rear of this portion is a bolt 17 the lower end of which extends through a slot 18 formed in the platform 12 70 of each roll stand and having a nut 19 threaded thereon and engaging at its upper end the lower face of the platform 12, as is well known construction in the art, for permitting adjustment of the block 15 and the lower back roll 16 towards and from the lower front roll 13.

The rolls 13 and 16 are each of a sectional construction in which a plurality of short sections are keyed together at their ends to provide a single continuous elongated shaft which is journaled at a plurality of intervals in the roll stands 5 and extending the entire length of the machine, as usual, the rolls being positively driven at different speeds by suitable gearing (not shown) at the end of the machine, at rates whereby the draft on the yarn, sliver or roving between the successive rolls is increased. The rolls 13 and 16 are each formed with fluted portions 20 and 21 respectively, at intervals along their length and are alternately arranged in spaced relation with smooth cylindrical spacing portions (not 15 shown) of a lesser diameter therebetween, as is the common construction in the art.

A driving roll 24 also in the form of a single continuous shaft of similar elongated sectional construction as the lower rolls 13 and 16 and extending 20 the entire length of the machine, is provided at intervals with a plurality of spaced bearing portions 25 which are journaled in the forward reduced portion of the block 15 in the roll stands. By loosening the nut 19, the rolls 16 and 24 being 25 journaled in the common bearing block 15 thus may be moved with the block and simultaneously positioned at desired adjusted distances towards or from the lower front roll 13. Positioned on the driving roll 24 between the successive bearing portions 25 and at spaced intervals therealong are a plurality of enlarged hubs 28 and 29 which, as shown in Fig. 3, form a rest or support members for purposes which will hereinafter be described. Located at intervals on the driving roll 24 and between the pair of hubs 28 and 29 is positioned an enlarged fluted hub portion or gear 30, the diameter of this gear being greater than the diameter of either of hubs 28 and 29, and employed for purposes to presently appear. 30 This gear and the hubs 28 and 29 may each be formed integral with the shaft of the roll 24 or they may comprise separate parts which are fixed in position on the roll. As illustrated in Fig. 2, the driving roll 24 is located below the line of 35 travel of the fibers of sliver or roving, which is designated at S by the dot and dash lines so as to be tangent to the peripheries of the fluted portions 20 and 21 of the lower rolls 13 and 16 respectively, and the arrangement is such as to permit my particular belt mechanism which will presently be described and embodying the present invention, to be mounted above the driving roll 24 and in a superposed cooperating relation thereto without changing the relationship of the 40 line of travel of the yarn, as indicated by the broken line S, whereby the latter may travel between the cooperating surfaces of a pair of juxtaposed belts of my intermediate belt unit.

As shown in Fig. 2 of the drawings, the block 60 15 has a rearward extension 30 thereon in which is mounted a pivot rod 31 to which may be fixed, as by suitable set screws, a plurality of cap bars 33. Ordinarily, there are more cap bars than roll stands, a cap bar being provided for each roll stand 65 10 and others being positioned intermediate of the stands, the bars being arranged for forward pivotal swinging movement over the rolls 13 and 16. As illustrated, each cap bar is of extensible construction, it being formed of two sections 34 and 35, and connected by a telescopic rod 36. The rear section 34 is shown as being provided with oppositely disposed vertical arranged channels or slots 37 having open ends at the top face of the cap bar and extend downwardly there- 70 75

from for loosely receiving trunnions or journals 38 at the ends of the rear upper rolls 40. The channels 37 may be provided as a deep cut in the top face of the arms 33 or in the opposite side 5 faces thereof as separate channels extending inwardly from the sides of the cap bar arm, in which latter case they extend in a vertical direction throughout the entire depth of the arms. Similarly, the front section 35 is provided with oppositely disposed vertically arranged slots 41 positionable above the lower roll 13 and form guides for loosely receiving the trunnions or journals 42 of the front top rolls 43, the rolls 40 and 43 being formed with spaced sections (not shown) which 10 are customarily provided with a leather or cork outer covering and adapted to rest upon the underlying fluted sections 20 and 21 of the bottom rolls 13 and 14 respectively. The above described parts have been shown in their conventional arrangement without the usual weighted saddle means for properly weighting the upper rolls 40 and 43 and maintaining them in place, as is well known in the art, such means forming no particular feature of the present invention. At a point 15 intermediate these channels 37 and 41 the cap bar 33 is thickened as at 45 to provide a lug which extends downwardly into close proximity to the lower drive member 24, and vertical channels 46 formed in this lug 45 are oppositely disposed and 20 extend throughout the entire depth thereof at a location above and in vertical alignment with the axis of the driving roll 24. These channels 46 and 48 form guides in which ride and are loosely supported the trunnions of the front belt guide 25 members and the belt driving rolls of my drawing mechanism, as will be presently more fully described.

As illustrated in the drawings, there is shown disposed between the sets of nip rolls one form 30 of apron or belt mechanism for feeding and conducting the sliver or roving to the drawing rolls, and according to the present invention it comprises a pair of endless belts or aprons 51 and 52 which are positioned on to encircle a pair of rotatable driving cylinders or rolls 54 and 55 respectively, each of which belts has insertable within 35 its loop its respective driving roll while the forward end of the belts 54 and 55 are positioned about and run over a pair of front guide members 57 and 58 respectively. The rolls 54 and 55 for the upper and lower belts have provided at each end journals or trunnions 60 and 61 respectively, adapted to loosely fit within and be removably mounted for sliding and rotary movement in the 40 vertical slots 46 formed in the oppositely disposed faces of adjacent cap bar arms 33. The rolls 54 and 55 are of similar construction of which the former is an idler roll, while the latter is adapted to be positively driven by the roll 24, the rolls 54 and 55 each are provided with a pair of spaced belt-driving sections 62 and 63, and an intermediate hub section 64 of reduced diameter, said sections 62 and 63 each being formed with cylindrical 45 end portions 65, 65' between which lies an intermediate portion 66 which is provided with a roughened surface formed either by knurling, milling or fluting the same. Located intermediate between the belt driving sections 62 and 63 of the lower roll 55 is a driving hub or gear 68 which is of approximately the same diameter as 50 that of the belt driving sections of this roll so as to be adapted for intermeshing with and have positive driving connection with the driving gear 29 of the lower elongated driving roll 24 when 55 the belt mechanism assembly is mounted in

proper operating position in the machine, as will be hereinafter described.

As illustrated, the guide frame for each set of belts 51 and 52 is loosely mounted on the lower rotatable cylinder member or roll 55 and comprises a pair of side plates 70 and 71 and which may be connected by suitable strut members (not shown) and rigidly secured to the side plates to provide a unitary structure. The bottom edges of each of the side plates 70 and 71 are recessed, as indicated at 74 and 75 respectively, so as to permit them to fit over and embrace the reduced portions 76 and 77 respectively, of the lower roll 55 employed for driving the bottom belt 52. The side plates 70 and 71 also have their top edges 78 provided with upper recessed portions 79 and 80 to loosely receive and locate the top rotatable cylinder member or roll 51 by which the upper belt 51 is driven.

The side plates 70 and 71 each have positioned at their front portion a pair of guide bars 57 and 58 for the forward loops of the belts and which extend laterally between adjacent plates of each set and are integrally secured thereto in any suitable manner, as by screws 81. Provided at the 20 ends of each of the guide bars 57 and 58 are the projections 84 and 85 and are each formed with flat top and bottom faces which fit into a pair of spaced notches 86 and 87 having flat walls and 25 formed by slotting the front end faces of each of the plates 70 and 71. The guide bars 57 and 58 after having their projections 84 and 85 inserted in place in the notches 86 and 87 respectively are thus positioned in spaced relation one to the other and are encircled by the forward loops of the 30 belts 51 and 52 respectively, as shown in Fig. 5. The rear face of the plate 70 is provided with a rearwardly projecting hook portion 88 to receive the journals or trunnions at the ends of a clearer 35 roll 89 to engage the outer surface of a plurality 40 of lower belts 52.

In accordance with this construction, the screws 81 at each end of the guide bars thus rigidly secure them to the side plates 70 and 71 so that the entire assembly may be simultaneously 45 withdrawn as a unit from the cap bars 33.

As shown in Figs. 7 and 9, the guide bars 57 and 58 are each formed of relatively wide bar stock the front or leading edge of which is beveled and curved in order to provide a smooth tapered 50 rounded surface over which the inner circumference of the forward run of each of the belts travels. The guide bars 57 and 58 are shown as being of similar construction and thus may be 55 interchangeable one with the other in the side plates 70 and 71. The spacing between the guide bars 57 and 58 always should be, however, substantially greater than the thickness of the belts 51 and 52 so as to accommodate the regular passage of the sliver or roving between the cooperating surfaces of the belts without preventing the 60 proper functioning of the latter.

Referring to Figs. 10, 11 and 12, the construction there shown comprises a modified form of cradle device embodying my invention in which 65 the side plate 90 corresponds to the side plate 70 of the other device previously described, but in the modified form the front edge of the side plate 90 is shown as being provided with a projection 91 having shoulders 92 and 93 for positioning a 70 pair of guide bars 95 and 96, the ends of the latter being provided with projections 97 and 98, and the bottom and rear faces of the projections 97 and the top and rear faces of the projections 98 75 meeting rearwardly at a right angle corner 75

whereby they may be positioned into seating engagement in a right angular corner provided by the front edge portion and the shoulders 92 and 93, above described. When so mounted the projections 91 of the plates 90 serve to space the guide bars 95 and 96 so as to provide sufficient clearance for cooperating movement of the belts 51 and 52 respectively. The other side plate (not shown) in each set and employed in the modified construction of the apparatus will be formed similar to the inner side plate 71 shown in Fig. 9, as previously described, but will differ therefrom in that the front edge portion will be provided with the projection 91, as shown in the modified construction of plate shown in Fig. 10, in place of the slots 86 and 87.

It will thus be apparent that in accordance with the present invention, a construction of feeding device of the belt type is provided which has considerable advantages over any of the prior art constructions commonly employed in the art, the arrangement of the present invention being such as to permit the belt driving rolls 47 and 48 to be removed simultaneously from its support in the cap bar and to enable insertion or withdrawal of both cradles and the associated belts and guide bars and driving rolls as an entire unit assembly without the necessity for either stopping the complete machine or of severing the lower belt as has heretofore been the practice.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a drawing mechanism for textile slivers or rovings utilizing a pair of endless belts disposed one above the other in cooperating relation for conducting the slivers or rovings, the combination of a frame for laterally guiding the belts composed of spaced parallel side plates united together into a rigid unitary structure by two cross-bar guide members for internally guiding the front loops of the belts, said cross-bar belt guiding members being detachably secured at their opposite ends to said side plates in spaced relation at the front edge portions thereof, the opposite ends of each of said cross-bar members being provided with longitudinal projections having interfitting relation with shoulders formed on the front edges of said side plates, each of said cross-bars having a forwardly tapered front edge portion to engage the inner circumferential surface of an endless belt.

2. In a drawing mechanism for textile slivers or rovings utilizing a pair of endless belts disposed one above the other in cooperating relation for conducting the slivers or rovings, and upper and lower removable rolls driving the said belts, the combination of a frame for laterally guiding the belts composed of spaced parallel side plates united together into a rigid unitary structure by two cross-bar guide members for internally guiding the front loops of the belts, said plates having top and bottom recesses to detachably receive said rolls in parallel cross-wise relation between said side plates, said cross-bar belt guiding members being detachably secured at their opposite ends to said side plates in spaced relation at the front edge portions thereof, the opposite ends of each of said cross-bar members being provided with longitudinal projections having interfitting relation with shoulders formed on the front edges of said side plates, each of said cross-bars having a forwardly tapered front edge portion to engage the inner circumferential surface of an endless belt, said belts serving to maintain the driving rolls therefor in assembled position in the recesses in said frame to form a unitary demountable mechanism.

3. In a drawing mechanism for textile slivers or rovings utilizing a pair of endless belts disposed one above the other in cooperating relation, the combination of a pair of spaced parallel arm members hingedly mounted at one end for movement to and from a horizontal position with opposed channels, one in each of the oppositely disposed sides of said arm members, said channels being vertical longitudinally in the horizontal position of said arm members, a pair of rolls driving the said belts and removably supported at their ends one above the other in said channels for rotation therein, a frame for laterally guiding the belts composed of spaced side plates united together into a unitary structure by two cross-bar guide members for internally guiding the front loops of the belts, said plates having top and bottom recesses to receive said rolls and be mounted thereon, said cross-bar members being detachably secured at their opposite ends to said side plates in spaced relation at the front edges thereof, each of said cross-bar belt guiding members having a forwardly tapered front edge portion to engage the inner circumferential surface of an endless belt, said belts serving to maintain the driving rolls therefor in assembled position in said frame to form a unitary demountable mechanism removable as a unit from the channels in said arm members.

JOHN FREDERICK JACKSON.
